UNITED STATES PATENT OFFICE.

BERTON I. RIKE AND JOHN R. KLIN, OF DAYTON, OHIO, ASSIGNEES TO THE RIKE FOLDING BOX CO., OF DAYTON, OHIO, A CORPORATION OF OHIO.

PAPER PAIL.

No. 928,218.

Specification of Letters Patent.

Patented July 13, 1909.

Application filed May 19, 1909. Serial No. 496,951.

To all whom it may concern:

Be it known that we, BERTON I. RIKE and JOHN R. KLIN, citizens of the United States, residing at Dayton, in the county of Montgomery and State of Ohio, have invented certain new and useful Improvements in Paper Pails; and we do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to new and useful improvements in paper pails, such as are commonly used for conveying oysters, ice cream, and the like in small quantities.

The object of the invention is to provide a 20 paper vessel of the above type having a tight and neat closure which is easily and conveniently manipulated in opening and closing the vessel.

With the above object in view, the blank 25 from which the vessel is formed is of such shape that it may be cut from the material or stock with the least possible waste of material, and the cover or closure of the mouth of the vessel is such that any leakage of the 30 liquid contents of the vessel is rendered impossible and the cover or closure of the vessel is exceedingly firm and rigid when closed and is susceptible of withstanding an excessive amount of handling without materially 35 weakening the vessel.

In the accompanying drawings, Figure 1, is a plan view of a blank from which our improved paper vessel is formed. Fig. 2, is a perspective view of the paper vessel completed and closed. Fig. 3, is a perspective view of the vessel partially formed. Fig. 4, is an enlarged detail sectional view of the meeting edges of the cover showing one of the clamps or fasteners. Fig. 5, detail views 45 of the bail end. Fig. 6, is a top view of the mouth of the vessel showing it partly closed.

In a detail description of the invention, similar reference characters indicate corresponding parts.

50 The blank from which the pail is formed is

cut and scored to provide a rectangular bottom 1 with four upright sides 2, 2 and 3, 3, the former being hereinafter termed the sides of the vessel, and the latter the ends of the vessel. The side and end walls 2 and 3 55 are joined by the usual upright triangular folds 4 and 5 which fold against the outer sides of the side walls 2, 2. The side walls 2, 2 have end extensions 6, 6 which bend inwardly on intervening score lines 6', 6', and 60 the extensions 6, 6 terminating in reinforcing flaps 9, 9 between which and the extensions 6, 6 there are portions 12, 12' which fold on the score lines 9' between the parts 6 and 9, the said portions 12 and 12' forming the 65 outer meeting portions of the cover, see Fig. 2. The reinforcing flaps 9, 9 bend outwardly and are secured to the outer sides of the marginal folds 11, 11 which extend from the triangular folds 4, 4. These flaps 9, 9 may 70 be secured in any suitable manner, either by a fastening device or by a suitable adhesive substance applied thereto. The marginal folds 10 and 11 it will be seen, are extensions of the triangular folds 4 and 5, and when 75 these parts are folded with the folds 4 and 5 they both, to-wit: the folds 10 and 11 lie against the outer sides of the extensions 6 of said side walls 2, 2, and the flaps 9, 9 secure the parts 6, 10 and 11 snugly together. 80 The extensions 6, 6 incline inwardly at the top of the vessel when said vessel is closed.

It will be observed from the blank as shown in Fig. 1, and the partly-formed vessel as shown in Fig. 3, the margins of the 85 folds 10 and 11 incline downwardly from near the corners of the vessel when they are folded, and bend on score lines 10' which are continuations of the score lines upon which the folds 4 and 5 bend. The reinforcing 90 flaps 9, 9 bend upon the score lines 9', and when so bent the folds 12' lie against the outer sides of the folds 12, 12, and these folds 12 and 12' form the engaging portions of the mouth of the vessel as before stated, and 95 which are held together by metallic fasteners 13 which are secured in a position to clamp over the folds 12, 12' and hold the mouth of the vessel rigidly together. When the closure folds 12, 12' are thus brought together 100

and held by the clamps 13, they bend on the score lines 6" and 9". The free ends of the metallic fasteners 13 have portions stamped therefrom which provide inturned edges 14 which, when said fasteners are made to clamp the mouth of the vessel, embed themselves into the outer surface of the closure folds 12' on one side and rigidly prevent the closure of the vessel from having any looseness or lateral movement.

It will be seen from Fig. 3, the fasteners 13 are attached to the folds 12, 12' on one side. The closure of the vessel is very firm and cannot be moved laterally to any extent whatever owing to this engagement of the fastening devices 13. There are two of said fastening devices, one at each end of the closure. The end walls 3, 3 of the vessel have inwardly-inclined extensions 7 joined immediately thereto and which bend inwardly on score lines 3'. Joining the extensions 7 are two marginal extensions 8 which bend upon diagonal score lines 7' which separate them from the extensions 7 and thus enable the parts 7 to bend in as shown in Fig. 2. The folds 8, 8 terminate in marginal portions 8' which extend and form parts of the margins of the folds 11. The margins 8', 8' bend on score lines between parts 7 and 8, and when said margins 8', 8' are folded in as in Fig. 2, they lie parallel with and are engaged and inclosed by the meeting parts 12, 12' and thus coöperate with the parts 12, 12' in forming a liquid-tight closure, see Fig. 4. When the closure of the vessel is brought together as in Fig. 2, the end extensions 7 lie inwardly on inclines as before stated, and the marginal extensions 8' lie against the inner sides 12, 12 of the parts 12', 12' which, as before stated, form the meeting edges of the closure and are held together by the metallic fasteners 13. In this position, the folds 8, 8 lie above the inwardly-lying extensions 7, 7, and the mouth of the vessel is most effectually closed against any slopping of the liquid contents.

The wire bail 15 has its ends formed in hooks 16 which connect with eyes 17 on opposite sides of the vessel. The eyes 17 are formed of wire which penetrate the top flaps 9, the triangular folds 4 and 5 and the side walls 2, and are clenched against the inner sides of said side walls and thus hold the triangular folds 4 and 5 and the flaps 9 in contact with the side walls.

55 We claim:

1. A rectangular paper pail having side and end walls joined by triangular folds which lie against the side walls, said side walls and triangular folds having closure extensions which are reinforced by down-turned reinforcing flaps extending from the upper ends of the closure extensions of the side walls, the margins of the side wall clo-

sure extensions and the triangular fold closure extensions, together with the margins of 65 the reinforcing flaps forming the meeting portions of the vessel closure, and metallic fasteners binding said meeting portions rigidly together to close the mouth of the vessel.

2. A rectangular paper pail having side 70 and end walls joined by triangular folds which lie against the side walls, said side walls and triangular folds having closure extensions which are inclosed on their outer sides by down-turned reinforcing flaps that 75 extend from the upper ends of the closure extensions of the side walls, the margins of the over-lapped portions of said closure extensions of the triangular folds, together with the margins of the side wall closure extensions 80 and the margins of the reinforcing flaps forming the meeting portions of the closure, and metallic fasteners binding said meeting portions rigidly together to close the mouth 85 of the vessel, said metallic fasteners penetrating said meeting portions on one side of the mouth of the vessel to maintain said meeting portions against any independent end-wise movement.

3. A rectangular paper pail having side 90 and end walls joined by triangular folds, the end walls having closure extensions which bend inwardly and constitute in-lying portions of the closure, the side walls having extensions which also bend inwardly and constitute out-lying portions of the closure, said side wall extensions being joined to reinforcing flaps which bend outwardly and downwardly and unite the closure extensions of the triangular folds and the closure extensions of the side walls, the margins of the closure extensions of the end walls and the margins of the closure extensions of the side walls and the margins of the closure extensions of the triangular folds providing the meeting 100 edges of the vessel closure, and metallic fasteners clamping said meeting edges together 105 to close the mouth of the vessel.

4. A rectangular paper pail having side and end walls joined by triangular folds, the side walls having closure extensions, the triangular folds having extensions which fold against the closure extensions of the side walls, reinforcing flaps extending from the closure extensions of the side walls and folding against said closure extensions and against the extensions of the triangular folds, the closure extensions of the side walls, and the reinforcing flaps having a plurality of parallel score lines intervening between 120 them which enable the closure extensions to be brought together at the mouth of the vessel, the end walls having closure extensions which bend inwardly over the mouth of the vessel and portions of which lie against the 125 inner sides of the closure extensions of the

side walls, the margins of the closure extensions of the side walls and the margins of the closure extensions of the end walls, coöperating in closing the mouth of the vessel, and 5 metallic fasteners secured to one side of the closure and adapted to embrace the other side to maintain said closure closed over the mouth of the vessel.

In testimony whereof we affix our signatures, in presence of two witnesses.
